UNITED STATES PATENT OFFICE.

EDGAR W. BURKE, OF MONUMENT, KANSAS.

BANANA RACK.

Application filed February 26, 1923. Serial No. 621,218.

To all whom it may concern:

Be it known that I, EDGAR W. BURKE, a citizen of the United States, residing at Monument, in the county of Logan and State of Kansas, have invented certain new and useful Improvements in Banana Racks, of which the following is a specification.

My invention relates to improvements in banana racks, the primary object thereof residing in the provision of such a rack that may be expeditiously attached to a desirable support the said rack adapted for swinging movement thereon for permitting of the bananas to be easily secured to the rack, after which the same may be swung forwardly to its proper supporting position.

A further object of my invention is the provision of such a rack that is comparatively simple of construction, and of such a nature as to be readily secured to a desirable support.

With the above and other objects in view as the nature of the invention is better understood, the same consists in the combination and arrangement of parts hereinafter shown and described.

In the drawings forming part of this application, like numerals of reference indicate similar parts in the several views, and wherein:

Figure 1 is a side elevational view of my improved rack, the same being shown in position upon a store counter.

Figure 2 is a rear elevational view thereof.

Figure 3 is a sectional view taken upon the line 3—3 of Figure 2, and

Figure 4 is a perspective view of one of the bracket members employed in conjunction with my invention.

Referring to the drawings in detail, A indicates a conventional form of counter, used in grocery stores, and the like. Upon the top of this counter and preferably adjacent one end thereof are a pair of spaced brackets 5, the same being rigidly secured to the counter and comprising bottom walls 6 and vertical side walls 7, the edges of these side walls being preferably inclined as more clearly shown in Figure 4.

My rack per se, includes a pair of vertically and forwardly extending legs 8, which are preferably in the form of pipe sections, the top ends thereof being slightly

inwardly, as more clearly shown in Figure 2, for adding strength to these legs. The lower ends of these legs 8 are pivotally secured between the side walls 7 of the said brackets 5, through the instrumentality of removable pivot pins 9, and connected to said ends of the legs 8, are forwardly extending brace arms 10, consisting also of pipe sections, and joined at their front ends by a connecting pipe 11. Formed upon the front ends of the said arms 10 are vertically extending pipe sections 12, the upper ends thereof being welded or brazed to the said pipes constituting the legs 8.

Within the front ends of the pipe members constituting said legs 8 are the ends of a hanger 13, these ends being brazed, welded or otherwise rigidly secured within the said ends. This hanger 13 is preferably of the shape as shown, the front end thereof being formed with a hook 14, to which is secured one end of a banana stalk B, and in view of the above description, it will be at once appreciated that in positioning a stalk of bananas upon my rack, the same is swung rearwardly off of the counter A, at which time, the banana stalk may be attached to the hook 14 of the hanger 13, after which the rack is forcibly swung forwardly upon its pivots 9 into a position clearly shown in Figures 1 and 2, the said arms 10 as well as the vertical pipe sections 12 assisting in maintaining the said rack in such a position.

In view of the above description, it is believed that the advantages and operation of a rack of this character will be readily appreciated by those skilled in the art, and although I have herein shown and described the preferred embodiment of the invention, it is nevertheless to be understood that minor changes may be made therein, without departing from the spirit and scope of the invention as claimed.

Having thus described my invention, what I claim as new, and desire to secure by Letters-Patent is:

A rack comprising bracket members having plane base surfaces adapted to be mounted upon a support and side portions provided at the side edges of the base portions, leg members pivotally mounted to the side portions of the bracket at points above the base surfaces thereof and between the side portions thereof, said legs having arm

portions adapted to engage the base surfaces of the brackets and retain the legs at acute angles with relation to the planes of the base surfaces of the brackets, brace portions connecting the ends of the arms with the intermediate portions of the legs, converging hangers carried at the upper

portions of the legs and coming together at a point between the legs and provided with a hook at their point of connection 10 with each other.

In testimony whereof I affix my signature.

EDGAR W. BURKE.
